UNITED STATES PATENT OFFICE.

EDWARD SOKAL, OF NEW YORK, N. Y., ASSIGNOR TO AMERICAN KATALITE CORPORATION, OF NEW YORK, N. Y., A CORPORATION OF DELAWARE.

INTERNAL-COMBUSTION ENGINE.

Application filed May 5, 1927. Serial No. 188,893.

This invention relates to internal combustion engines, to correlated improvements and discoveries whereby and wherewith the operation thereof is enhanced, and more particularly to the prevention of detonation in the combustion chamber thereof.

An object of the invention is directed to the provision in an internal combustion engine of an improved detonation counter-actant.

Another object is to provide an improved method of permanently preventing detonation in an internal combustion engine.

A further object is to provide an improved coating composition which may be affixed to the walls of the combustion chamber of an internal combustion engine to prevent detonation therein.

In my co-pending application, Serial No. 42,583, filed July 9, 1925, patented June 7, 1927, No. 1,631,702, I have shown that the tendency toward detonation in an internal combustion engine, particularly the pronounced tendency thereto in high compression engines, may be counteracted by fixedly disposing within the combustion chamber of the engine a material capable of undergoing a reversible endothermic, i. e., heat-absorbing, change within the range of temperatures and amid the other conditions existent in the engine during operation, by means of which a cooling effect is exerted upon the gaseous mixture within the chamber with a resultant counteraction of detonation.

While it is well recognized that detonation of the gaseous mixture within a combustion chamber can be counteracted by cooling the mixture, no theory offered in explanation of this phenomenon has been universally accepted. It is my view that detonation, or knocking, in internal combustion engines, is mainly due to a decomposition or breaking down of the unburned fuel, or in other words, to the dissociation of the larger molecules of the fuel under the influence of heat and pressure into a greater number of smaller molecules, whereby there is caused a sudden rise of pressure. This rise of pressure may not be indicative of the true pressure condition within the whole body of the fuel-air mixture, but is rather in the nature of a localized impact. This view is supported by the following considerations: First, the detonating tendency of various fuels is practically a

function of their thermal stability, for example, the tendency to detonate decreases in the following order: Kerosene, ordinary gasoline, aromatic gasoline, benzol, alcohol and hydrogen, and the thermal stability increases in the same order. Second, the indicator diagram of detonating engines shows a very rapid rise of pressure which lasts only a very short period of time, is followed by an equally rapid decline, frequently occurs several times at the beginning of the expansion stroke, the peaks becoming smaller each time, and these rises of pressure are of such short duration that the corresponding pressure volume area is too small to represent an appreciable amount of useful work and hence they manifest themselves as destructive impacts. Third, detonation is accompanied by lost power, deposition of carbon and great loss of heat to the water jacket, which loss of power and deposition of carbon may be considered natural results from the decomposition of the fuel, and the loss of heat to the water jacket is probably due to radiation caused by glowing particles of carbon and to the impacts. Fourth, it has been shown that various factors which cause an increase in the rapidity of combustion and make the combustion more complete have a rather pronounced effect in counteracting detonation. This would seem to follow as an indirect result of the fact that the molecules of the fuel cannot simultaneously undergo a reaction of combustion and of decomposition.

In my patent above referred to, I have disclosed as an exemplification of a detonation counteractant suitable for use in accordance with the invention, a material, the melting point of which is such as to render it capable of undergoing a reversible change from solid to liquid state under the conditions of engine operation, and I have particularly suggested the use of lead, antimony and tellurium.

The present application is a continuation in part of my co-pending application, Serial No. 142,247 filed October 18, 1926, patented June 7, 1927, No. 1,631,703, wherein it is disclosed that an especially effective detonation counteractant for such use is a non-fugitive, preferably solid, material which is capable under the conditions of engine operation of undergoing a heat-absorbing (endothermic)

change at the higher range of temperatures existent within the combustion chamber of the engine in which it is employed so as to be converted into a different non-fugitive, 5 preferably solid, chemical material, which latter material is capable under the conditions of engine operation of undergoing, at the lower range of temperatures existent within the combustion chamber, a heat-releasing (exothermic) change so as to restore 10 itself for further heat-absorbing action. It will be realized from the above that I use a material which undergoes a reversible chemical change under operating conditions, 15 and that the original substance disposed within the chamber may contain a material appearing on either side of the equation expressing the change, or both. Accordingly, with a view to simplicity of definition, the 20 term "chemically endothermically reactive material", as hereinafter employed, is to be understood to designate either a material falling within the definition of my improved detonation counteractant given above, or a 25 substance which is convertible into such material under the conditions of engine operation. It will be appreciated in this connection that since the invention relates to internal combustion engines, the term "chemically 30 endothermically reactive material" as employed hereinafter includes only such substances as will undergo the desired reactions within the range of temperatures and under the other conditions found within the 35 combustion chamber of the engine in which it is employed.

A chemically endothermically reactive material is particularly advantageous for use as a detonation counteractant within the 40 combustion chamber of an internal combustion engine because of the marked heat absorption during the endothermic reaction, with the consequent high cooling effect upon the gaseous mixture. Furthermore, when 45 there is employed a solid material which is converted into another solid material under the conditions contemplated by the invention, a further advantage is to be found in the elimination of any possibility of the loss 50 of the detonation counteractant by the escape of a material which has been converted into a fluid state.

In practice, a material capable of undergoing a reversible chemical change which is 55 endothermic during the power stroke, when the temperatures within the chamber are the highest and the consequent tendency toward detonation is the greatest, is fixedly disposed within the combustion chamber of an 60 internal combustion engine, preferably in the form of, or as an ingredient of, a coating applied to certain portions of the walls of said chamber. This coating is especially effective when applied to certain of those portions 65 of the chamber walls which are hottest

during operation, as, for example, the exposed surface of the piston and/or the exposed surface of the exhaust valves.

The present invention is directed primarily to the use of a chemically endothermically reactive material of the copper type, i. e. copper and its compounds. It has been found, for example, that basic copper carbonate ($\text{Cu}(\text{OH})_2 \cdot \text{CuCO}_3$) is an effective detonation counteractant when present in a finely divided condition on those portions of the chamber walls which are hottest during engine operation, and that this carbonate is readily formed when a coating containing powdered metallic copper is present on the walls of the combustion chamber. Moreover, the known facts relating to the reactivity of these two materials suggest that the reversible reaction occurring within the chamber during operation may be expressed by the equation:

wherein the symbols $+$ Δ and $-$ Δ indicate absorption and release of heat, respectively. It is, however, to be understood that this suggestion is based partly on theoretical considerations, and that some other equation may better express the actual effective reversible reaction which occurs. The known facts are that, under the conditions of engine operation, basic copper carbonate is readily formed on the surface of a coating containing copper powdered; and that when either powdered metallic copper or powdered basic copper carbonate is utilized in accordance with the invention, a marked decrease in detonation is secured. It will be appreciated, however, that the invention is not so limited as to exclude other copper carbonates which may act endothermically, or which may be convertible into a carbonate which so acts, or to exclude other copper-containing materials besides metallic copper (such, possibly as the oxides or hydroxides of copper) which are convertible into a copper-containing material which acts endothermically under engine operating conditions.

In view of the foregoing, it will be understood that wherever, for the sake of uniformity of expression in this and applicant's copending application, the term "copper-containing substance of the carbonate-oxide type" is employed below, that the term is intended to refer either to an endothermically reactive copper carbonate, or to any other material (including metallic copper) which is convertible into such carbonate under the conditions contemplated by the invention.

The accompanying drawing is a partly sectional view exemplifying a form of the invention. In this exemplification a cylinder block 1, together with a high compression cylinder head 2, provides a combustion

chamber 3 into which the contacts 4 of the spark plug 5 extend. A portion of the wall of the combustion chamber is provided by a piston head 6 on the surface of which is a coating 7 containing a relatively permanent chemically endothermically reactive material of the copper type in a finely divided condition. Another portion of the wall of this chamber is provided by the surface of an exhaust valve 8 on which there may also be provided a coating 9 which may also contain a relatively permanent chemically endothermically reactive material of the copper type in a finely divided condition.

15 It is to be noted that the chemical changes occurring during ordinary operation probably take place only in the exposed surface layer of the detonation counteractant, and also that even on this layer each molecule 20 of the material is probably not converted under ordinary conditions, but that the reaction occurs merely in a proportion of the molecules sufficient to exert the required cooling effect or to restore the material for 25 further heat absorption, as the case may be.

In order properly to secure it in place, the improved detonation counteractant may be applied to the desired portions of the chamber walls in a finely divided condition 30 and in admixture with a suitable binder, such as a silicate. For example, an intimate mixture of powdered copper (or other chemically endothermically reactive material of the copper type), and a silicate binder in 35 substantially equal proportions, or such other proportions as may be dictated by the conditions of the particular case, may be applied in the form of a coating on the exposed surface of the piston head, and/or such other portions of the walls as may be 40 desired. The application may be accomplished by cleaning the desired surface area, coating such area with the detonation counteractant, and baking or setting. This procedure 45 may be repeated, if desired, until several coats have been applied. Electrolytic copper is especially desirable for such use because of its marked activity. The amount of the improved detonation counteractant to 50 be applied in a particular type of engine may be readily determined by suitable tests indicating the proper surface area to be coated in order to obtain efficient operation.

It has also been found that particularly 55 satisfactory results are obtained when the initial coating contains metallic copper and litharge. In fact, comparative tests have demonstrated that better results are secured by the use of such a mixture than by the use 60 of either copper (or basic copper carbonate) or litharge (or lead carbonate) alone. This may be because of a cumulative effect of the two types of materials, due, possibly to the fact that they are most effective at slightly 65 different temperatures; or it may be because

of some catalytic effect, such, possibly, as a catalytic effect of the copper on a lead carbonate-litharge reaction, or vice versa. Experimental evidence indicates that the latter is probably the case, and that the increase 70 in anti-detonating effect is probably due to the catalytic action of the copper on the reactions undergone by the litharge or other chemically endothermically reactive material.

At the present time the phenomenon of detonation, or knocking, during the operation of internal combustion engines is of much interest because, other conditions being equal, it is more pronounced with engines of high 80 compression ratios. Accordingly, this tendency to detonate with a given fuel becomes practically a limiting factor for improvement in the thermal efficiency and power output through an increase in the compression 85 ratio. This is particularly the case with the "constant volume cycle" type of engine which is used almost exclusively in automobiles and in aeroplanes and also to a considerable extent in small marine and station- 90 ary engines.

It is true that there are other limiting factors, such as loss in mechanical efficiency, which may offset the gain in thermal efficiency after a certain increase in the compression ratio, but the limitation due to the injurious effects of detonation becomes operative before these other limiting factors exert their influence. Accordingly, it will be apparent that the present invention, because 95 of the marked effectiveness of a chemically endothermically reactive material as a detonation counteractant, will permit the designing of engines having a higher compression ratio than has heretofore been possible. 100

Among the other advantages arising through the utilization of the detonation counteractant, mention may be made of the following: lack of detonation or knocking, 110 lower fuel consumption, more flexible operation of the engine, decrease in carbon deposition, and an increase in the thermal efficiency, particularly in connection with the use of high compression engines.

It is, of course, to be understood that the 115 invention does not contemplate the use of a material of such a nature that a compound appearing on either side of the equation expressing the reaction occurring within the chamber, has a known cracking effect or 120 other property which would tend to overbalance the effective anti-detonating effect produced by heat absorption during the endothermic reaction.

While the theory herein presented offers a 125 basis for an understanding of the manner in which the detonation counteractant may function, and while it is supported by known facts, it is to be understood, of course, that the operativeness and practicability of the 130

invention is not dependent upon or limited in any way by the correctness of such theory.

Since certain changes may be made in the detonation counteractant above described, 5 and different embodiments of the invention could be made without departing from the scope thereof, it is intended that all matter contained in the above description shall be interpreted as illustrative and not in a limiting sense.

It is also to be understood that the following claims are intended to cover all of the generic and specific features of the invention herein described, and all statements of the 15 scope of the invention which, as a matter of language, might be said to fall therebetween.

I claim:

1. In an internal combustion engine, the combination with a combustion chamber of 20 a coating disposed on certain of the walls of said chamber, said coating containing a relatively permanent detonation counteractant comprising a chemically endothermically reactive material of the copper type in a finely divided condition.

2. In an internal combustion engine, the combination with a combustion chamber of a coating formed on certain of the walls of 30 said chamber, said coating comprising a copper-containing substance of the carbonate-oxide type in a finely divided condition.

3. In an internal combustion engine, the combination with a combustion chamber of a detonation counteractant fixedly disposed 35 on certain of the walls of said chamber, said detonation counteractant comprising powdered metallic copper.

4. In an internal combustion engine, the combination with a combustion chamber of 40 a detonation counteractant fixedly disposed on certain of the walls of said chamber, said detonation counteractant comprising basic copper carbonate in a finely divided condition.

45 5. In an internal combustion engine, the combination with a combustion chamber of a coating disposed on certain of the walls of said chamber, said coating comprising a substance of the copper type and a chemically endothermically reactive compound of another metal.

55 6. In an internal combustion engine, the combination with a combustion chamber of a coating disposed on certain of the walls of said chamber, said coating containing metallic copper and litharge.

60 7. In an internal combustion engine, the combination with a combustion chamber of a coating disposed on certain of those portions of the walls of the chamber which are hottest under operating conditions, said coating containing a chemically endothermically reactive material of the copper type in a finely divided condition.

65 8. In an internal combustion engine, a

combustion chamber arranged for the reception of a gaseous mixture and fitted with a piston presenting an exposed surface to the gas in said chamber, said surface comprising a coating containing a chemically endothermically reactive material of the copper type in a finely divided condition.

9. As an article of manufacture, a piston head arranged for use within an internal combustion engine, the pressure surface 75 thereof having formed thereon a coating containing a chemically endothermically reactive material of the copper type in a finely divided condition.

10. In an internal combustion engine, the 80 combination with a combustion chamber of a coating disposed on certain of the walls of said chamber, said coating comprising a relatively permanent chemically endothermically reactive material of the copper type in 85 a finely divided condition, and a binder.

11. In an internal combustion engine, the combination with a combustion chamber of a coating comprising a copper-containing substance of the carbonate-oxide type in a finely divided condition and a silicate binder.

12. In an internal combustion engine, the combination with a combustion chamber of a coating comprising metallic copper in a finely divided condition and a binder.

13. In an internal combustion engine, the combination with a combustion chamber of a coating comprising basic copper carbonate in a finely divided condition and a binder.

14. A method of counteracting detonation 100 of the successive fuel charges in the combustion chamber of an internal combustion engine, which comprises permanently exposing to such charges a chemically endothermically reactive material of the copper type 105 in a finely divided condition.

15. A method of counteracting detonation 110 of the successive fuel charges in the combustion chamber of an internal combustion engine, which comprises forming an intimate admixture of a chemically endothermically reactive material of the copper type in a finely divided state and a silicate binder, and applying the resultant admixture to certain portions of the wall of the combustion 115 chamber of the engine.

16. A method of counteracting detonation 120 of the successive fuel charges in the combustion chamber of an internal combustion engine, which comprises applying a coating containing powdered metallic copper on certain portions of the wall of the combustion chamber of the engine.

17. A method of counteracting detonation 125 of the successive fuel charges in the combustion chamber of an internal combustion engine, which comprises applying to certain portions of the wall of the combustion chamber of the engine a coating containing metallic copper and litharge.

18. In an internal combustion engine, the combination with a combustion chamber, of a coating disposed on certain of the walls of said chamber, said coating containing a chemically endothermically reactive material and a catalyst.
19. In an internal combustion engine, the combination with a combustion chamber, of a coating disposed on certain of the walls of said chamber, said coating containing a chemically endothermically reactive material and a catalyst comprising copper.
20. In an internal combustion engine, the combination with a combustion chamber, of a coating disposed on certain of the walls
- of said chamber, said coating containing a chemically endothermically reactive lead compound of the carbonate-oxide type and finely divided copper.
21. In an internal combustion engine, the combination with a combustion chamber of a coating disposed on certain of the walls of said chamber, said coating containing a relatively permanent detonation counteractant comprising a chemically endothermically reactive lead compound in a finely divided state and a finely divided catalyst intimately admixed therewith.

In testimony whereof I affix my signature.

EDWARD SOKAL.
